Primary Examiner — Sharon S Oum*Assistant Examiner* — Vanessa Martinez(74) *Attorney, Agent, or Firm* — Jose Cherson Weissbrot(57) **CLAIM**

The ornamental design for an automobile light as shown and described.

DESCRIPTION

FIG. 1 is a perspective view of our new design. FIG. 2 is another perspective view thereof; FIG. 3 is a front view thereof; FIG. 4 is a rear view thereof; FIG. 5 is a left side view thereof; FIG. 6 is a right side view thereof; FIG. 7 is a top view thereof; FIG. 8 is a bottom view thereof; and, FIG. 9 is a partial enlarged view of the area labeled "9" in FIG. 1 thereof.

The broken lines in the drawings illustrate portions of the automobile light that form no part of the claimed design. The dot dash broken lines in FIGS. 1 and 9 delineate areas of the figures shown enlarged and form no part of the claimed design.
